UNITED STATES PATENT OFFICE.

LEONARD MATLOCK, OF RALPH, ARKANSAS.

AIRSHIP.

1,298,754.

Specification of Letters Patent.

Patented Apr. 1, 1919.

Application filed October 23, 1918. Serial No. 259,359.

To all whom it may concern:

Be it known that I, LEONARD MATLOCK, a citizen of the United States, residing at Ralph, in the county of Marion and State of 5 Arkansas, have invented a new and useful Airship, of which the following is a specification.

This invention relates to airships, one of its objects being to provide an airship having a gas container combined with a sustaining plane and adapted, when collapsed from any cause, to act as a parachute, thus to allow the machine to descend in safety.

Another object is to provide a machine of 15 this character having a number of propellers which can be adjusted angularly simultaneously, while in operation, thus to propel the machine forwardly or upwardly at any angle desired.

20 A still further object is to provide an airship the weight of which is so disposed that the machine will not turn over while in flight.

With the foregoing and other objects in 25 view which will appear as the description proceeds, the invention consists of certain novel details of construction and combinations of parts which will be hereinafter more fully described and pointed out in the 30 claims, it being understood that various changes may be made in the construction and arrangement of the parts without departing from the spirit or sacrificing any of the advantages of the invention as set forth in the 35 appended claims.

In the accompanying drawings the preferred form of the invention has been shown.

In said drawings—

Figure 1 is a side elevation of the machine.

40 Fig. 2 is a plan view thereof.

Fig. 3 is a section on line 3—3, Fig. 1.

Fig. 4 is a transverse section through the collapsed gas container in use as a parachute.

45 Fig. 5 is a transverse section showing one of the side propellers adjusted angularly out of normal position.

Fig. 6 is a horizontal section through a portion of the machine and showing the 50 means for actuating the side propeller supports to shift said propellers.

Fig. 7 is a section on line 7—7, Fig. 6.

Referring to the figures by characters of 55 reference, 1 designates the bottom plane and base of the machine provided with side struts

2 suitably braced, as at 3 and to the upper ends of which is attached a top plane 4. A combined deck and sustaining plane 5 is secured to and supported by the struts and extends laterally therebeyond to form upper sustaining wings 6. Lower wings 7 extend laterally from the struts and the outer edges of the upper and lower wings are connected by braces 8 which also extend upwardly and downwardly to the sides of the planes 4 and 1. Supporting wheels 9 are located under the bottom plane 1 and are journaled in spring strips 10 secured at their ends to the plane and reinforced by laminated elliptical springs 11. The upper portions of the 60 65 70 75 80 85 90 95 100 105 110 115 120 125 130 135 140 145 150 155 160 165 170 175 180 185 190 195 198 200 205 210 215 220 225 230 235 240 245 250 255 260 265 270 275 the outer edge portions of the wings 6 and a rod is slidably mounted in the standards 24 on each wing, as shown at 25. Each rod has a rack 26 meshing with each of the gears 5 22 so that when the rod is moved longitudinally the racks will rotate the gears 22 and cause all of the shafts 17 to rotate simultaneously.

A rack 27 is provided on each rod 25 and 10 meshes with a gear 28 on a transverse shaft 29. Two of these shafts are provided, one for each rod, and the two shafts aline and extend inwardly toward the center of the plane or deck 5 where they are provided with 15 gears 30 meshing with smaller gears 31 revoluble with hand wheels 32. Thus by rotating these wheels 32 the shafts 17 can be rotated as desired.

Longitudinal shafts 33 are journaled on 20 the struts 2 and each is provided with a pulley 34 receiving motion through a belt 35 from a pulley 36 driven by an engine 37. Pulleys 38 are secured to the shafts 33 and are adapted to transmit motion through belts 25 39 to the respective pulleys 20.

A longitudinal shaft 40 is journaled in the machine and has a propeller 41 at the front end thereof. This shaft is adapted to be driven by a separate motor 42 through belt 30 and pulley mechanism shown at 43.

With the various propellers in motion it will be apparent that the direction of flight of the machine can be controlled. The inflated balloon will assist the side propellers 35 in elevating the machine when said side propellers are adjusted angularly to vertical positions, or, in other words, to positions where they will rotate about vertical axes. By adjusting the side propellers so as to rotate about inclined axes the propellers 21 40 will pull the machine forwardly and upwardly. By operating the propellers at one side while the ones at the other side are stationary the machine can be caused to turn. 45 Suitable rudders 44 having any desired con-

trolling mechanism can be provided for steering the machine either or both laterally and vertically. As the rotation of the shafts 17 twists the belts 35 the springs 23 are provided to allow the shafts 17 to shift longitudinally and at the same time hold the belts 50 taut.

What is claimed is:—

1. In an airship the combination with superposed planes, and wings forming side extensions of one of the planes, of slidable and revoluble transverse shafts supported by the wings, a shaft extending transversely of and movable with each of said transverse shafts, a propeller thereon, means for driving the 60 propeller shafts, means for simultaneously rotating the slidable and revoluble shafts to adjust the propeller shafts angularly, and yielding means for retarding the sliding movement of the shafts to hold the driving 65 means taut.

2. In an airship the combination with a plane having laterally extending wings, of transverse shafts supported by the wings and mounted to slide and rotate, propeller 70 shafts supported by and extending transversely of the said transverse shafts, gears upon the transverse shafts, racks slidably mounted and engaging the gears, means for actuating the racks to simultaneously rotate 75 the transverse shafts and adjust the propeller shafts angularly, drive shafts, belts connecting the drive and propeller shafts, and yielding means for controlling the sliding movement of the transverse shafts to hold 80 the belts taut during said angular adjustment.

In testimony that I claim the foregoing as my own I have hereto affixed my signature in the presence of two witnesses.

LEONARD MATLOCK.
